UNITED STATES PATENT OFFICE.

ROLO S. EWERS, OF HOXIES, KANSAS, ASSIGNOR OF ONE-HALF TO LINDEN KIRLIN, OF BEATTIE, KANSAS.

HEATER FOR INTERNAL-COMBUSTION-ENGINE INTAKE-MANIFOLDS.

1,283,125.

Specification of Letters Patent. Patented Oct. 29, 1918.

Application filed February 9, 1917. Serial No. 147,932.

To all whom it may concern:

Be it known that I, ROLO S. EWERS, a citizen of the United States, residing at Hoxie, in the county of Sheridan and State 5 of Kansas, have invented certain new and useful Improvements in Heaters for Internal-Combustion-Engine Intake-Manifolds, of which the following is a specification.

10 This invention relates to heating attachments for internal combustion engines, and has for its object to produce means for infallibly insuring the quick starting of the engine, if in proper working order, regardless of the temperature of the engine or of 15 the liquid fuel in the carbureter thereof.

More specifically my object is to produce means for safely heating the intake manifold to a high degree in close proximity to 20 the discharge end thereof, for the purpose of insuring the proper vaporization of the liquid fuel drawn from the carbureter through the intake manifold, by the suction produced by cranking the engine.

25 A further object is to produce an intake manifold heater of the character set forth, which is of simple, strong, durable and cheap construction, and which can be easily and quickly attached to or removed from 30 position.

With these objects in view the invention consists in certain novel and useful features of construction and combinations of parts as hereinafter described and claimed; and 35 in order that it may be fully understood reference is to be had to the accompanying drawing, in which:

Figure 1 is a fragmentary elevation of the intake manifold of an internal combustion engine, equipped with a heater embodying my invention.

Fig. 2 is an enlarged vertical section on the line II—II of Fig. 1.

Fig. 3 is a section on the line III—III of 45 Fig. 1.

Referring to the drawing in detail, 1 indicates the intake manifold of an internal combustion engine and 2 the branches of the manifold, leading to the cylinders of the 50 engine, not shown. A casing mounted upon the manifold and inclosing the branches thereof for a large proportion of their length, is constructed as follows: 3 indicates the body portion or trough, the same

being of substantially V-shape in cross section, and provided in its opposite sides and near its bottom with air inlet holes 4. It is also provided in planes adjacent the upper edges of said holes with cross pieces 5, and in one end wall with a hole 6. Both end 60 walls are also provided in their upper edges with semi-circular openings 7 of substantially the same radius as the branches of the intake manifold.

The front wall of the trough is provided 65 at its upper edge with a down-turned flange or shoulder 8 for a purpose which herein-after appears, and with a central semi-circular opening 9 of substantially the same diameter as openings 7.

The cover 10 of the casing is hinged at 11 to the upper edge of the rear wall of the trough, and is provided with a pair of depending snap hooks 12, adapted to engage flange or shoulder 8 and automatically lock 75 or fasten the cover and trough together. The cover is provided with a semi-circular opening 13 which, conjointly with opening 9, snugly receives and accommodates the intake manifold 1 at the point thereof from 80 where the branches 2 issue. The cover is also provided in its end walls with semi-circular openings 14 which, conjointly with openings 7, snugly receive and accommodate 85 the branches of the intake manifold, it being noted in this connection that when the casing is fitted upon the intake manifold, as explained, and the cover is latched to the trough, the former constitutes the means whereby the casing is supported upon the 90 manifold, and that by merely disengaging the latches it is possible to instantly remove the attachment from position.

As a convenient means for generating heat within the casing, without any possibility of danger through the proximity of the carbureter, I provide a wicking torch, the same comprising a perforated cylinder 15 containing an absorbent material 16 and provided at one end with a handle 17. For 95 convenience the handle is provided with an enlarged portion or collar 18, which forms a closure for the opening 6 when the wicking torch is in position, and said enlargement or collar is provided with a circumferential 100 groove 19 to receive that portion of the end wall of the trough which forms the lower edge of opening 6, so that through vibration

of the engine or otherwise, there will be little danger of the wicking torch becoming accidentally dislodged from position, it being noted by reference to Figs. 1 and 2 that 5 said torch also rests upon the bridge or cross piece 5 so that when in operative position, the torch shall lie above the plane of the openings or holes 4.

When it is desired to heat the branches 10 of the intake manifold preliminary to cranking the engine in cold weather, the operator can dip his torch into gasoline and then slip the torch through the opening 6 to the position shown in the drawing. A lighted 15 match is then applied to the torch, and the flame therefrom is caused by the draft through openings 4 and 10^a in the upper part of the cover, to completely envelop the incased portions of the branches of the 20 manifold and thus very quickly heat the same to a vaporizing temperature without any danger through the proximity of the flame to the carbureter.

The heating of the branches of the intake 25 manifold in close proximity to the discharge ends of said branches; that is, to the cylinders of the engine, insures the supply of a hot explosive mixture to the cylinders and therefore insures explosive action in the 30 cylinders when the engine is cranked.

I have found by practical experience that the mere application of heat to the carbureter of a motor car engine is not effective for quick starting purposes in very cold 35 weather. Many methods are resorted to in the endeavor to raise the temperature of the gasoline in the carbureter, but by no method with which I am familiar can it be raised safely to a temperature which insures complete 40 vaporization without the possibility of condensation in its passage through the cold intake manifold to the cylinders of the engine. I have found, however, that by the application of heat to the intake manifold 45 adjacent to the cylinders of the engine, that the gasoline and air drawn from the carbureter can be raised to such a temperature that the mixture will instantly explode by the production of a spark, and that this is

true regardless of temperature and atmospheric conditions. 50

From the above description it will be apparent that I have produced a heating attachment for internal combustion engines which embodies the features of advantage 55 enumerated as desirable in the statement of the object of the invention, and which obviously is susceptible of modification without departing from the principle and scope or sacrificing any of the advantages of the 60 invention.

I claim:

1. The combination with the branches of an intake manifold for internal combustion engines, of a casing through which the said 65 branches extend, provided with air-inlet openings below and air-exhaust openings above the said branches, and with an opening near its lower end, a torch within the casing, having a handle extending through 70 said last-named opening, and means for supporting the torch in a plane above that of the said air-inlet openings.

2. The combination with the branches of the intake manifold of an internal combustion engine, of a casing fitting upon and enveloping a part of said branches, and comprising a lower or trough member and an upper or cover member hinged to the trough member; said members having means 75 for fastening them in closed relation and also having draft openings below and above the plane of the branches of the intake manifold, and openings for the accommodation of the intake manifold at the point from 80 which the branches issue, a torch removably projecting into the trough of the casing, and means for supporting the torch in a plane between that of the branches of the intake manifold and the draft openings through 85 90 which air enters the casing.

In testimony whereof I affix my signature in the presence of two witnesses,

ROLO S. EWERS.
